CLAIM

The ornamental design for a sensor cover, as shown and described.

DESCRIPTION

FIG. 1 is a front, left perspective view of the sensor cover. FIG. 2 is a left side elevational view thereof.

FIG. 3 is a right side elevational view thereof.

FIG. 4 is a front elevational view thereof.

FIG. 5 is a rear elevational view thereof.

FIG. 6 is a top plan view thereof; and,

FIG. 7 is a bottom plan view thereof.

The broken line showings of the recesses are for the purpose of illustrating portions of the article and form no portion of the claimed design.
